UNITED STATES PATENT OFFICE

JOHN B. BASKERVILLE, OF ROANOKE, VIRGINIA, ASSIGNOR TO IMPACTOGRAPH CORPORATION, OF ROANOKE, VIRGINIA, A CORPORATION OF VIRGINIA

IMPACT RECORDER

Application filed July 3, 1926. Serial No. 120,339.

The present invention consists of an impactograph and is designed as an improvement over my issued Patent #1,577,160, having for an object the provision of recording mechanism which is actuated in response to impacts sustained by railway rolling stock while in transit.

Another object of the invention is to provide highly sensitive and selective mechanism which promptly responds to impacts and effects a record thereof when the impacts are of predetermined intensity.

A coordinate object of the invention is to provide a mechanism which promptly responds to impacts of predetermined intensity to make a record thereof, successive records being made as the intensity of the impacts is increased.

Other objects of the invention will be apparent from the following description of the present preferred forms of the invention taken in connection with the accompanying drawing, wherein:—

Fig. 1 is a longitudinal section view of one form of impactograph constructed in accordance with the present invention.

Fig. 2 is a transverse sectional view of the same.

Fig. 3 is a perspective view of the marker abutment showing connecting parts thereof removed.

Fig. 4 is a longitudinal sectional view of another form of impactograph constructed in accordance with this invention.

Fig. 5 is a transverse sectional view thereof; and

Fig. 6 is a perspective view of the marker abutment used in the form of invention illustrated in Figs. 4 and 5.

The present invention embodies a casing 7 which may be of any desired configuration and may be made of wood, metal or other suitable material. In the present instance the casing consists of two hingedly connected parts, the lid of the casing shown in Fig. 2 being provided with an opening 8 in one side thereof for a purpose hereinafter set forth.

The lid of the casing shown in Fig. 4 is provided with openings 9 in the ends thereof

for a purpose which will also be hereinafter set forth.

The impactograph as an entirety consists of mechanism mounted in the casing 7 which embodies certain elements or parts which are movable by impacts sustained thereby in order to impinge against record receiving means so that the means will bear indicia corresponding to the time the impact was sustained and the severity of the impact. This mechanism consists of a frame generally designated 10 which may be made of metal or like material. In the form of invention illustrated in Figs. 1 and 2 the frame embodies a base equipped with an inverted U shape superstructure 11. The sides of the superstructure fixedly receive the terminals of an axle or shaft 12 which latter has pivotally mounted thereon a series of segmental arms 13. The upper end of each arm issues into a segment 14 which has a portion of its periphery removed, approximately midway its ends, to provide a depression 15. The lower end of the segment is equipped with a discal weight 16, the discs varying in diameter and correspondingly varying in weight. Each disc has a stud 17 extended from its periphery at a point diametrically opposite to the segmental arm. This stud is adapted for connection with one end of a helical spring 18, the opposite end of said spring being engaged with a stud 19, which rises upwardly from the base of the frame 10. The abutments 13 are suitably spaced by collars 20 as illustrated in Fig. 2.

The mechanism further embodies a record receiving means which in the present instance embodies a roller 21 upon which paper or other indicia receiving flexible means 22 is mounted. The paper 22 or like means is adapted to be trained across the upper faces of the segments 14 and has its free end engaged with a take-up drum 23. This drum is rotated by suitable clock mechanism 24 the stem of which latter projects as indicated at 25, adapted for the reception of a key which may be inserted through the opening 8 in the top of the casing in order to wind the clock mechanism.

The sides of the frame 10 are provided, ad-

5 jacent the vertex thereof, with vertically extending slots 24 which receive the opposite reduced terminals 25' of a marker abutment 26. The abutment 26 is V-shape in cross section and has the apex thereof arranged to lie in close proximity to the paper 22 directly above the depression 15 in the segments 14. The marker 26 normally lies at the base of the slots 24 but may be moved vertically therein 10 under pressure of the segments, in a manner hereinafter set forth. The upward movement of the marker is limited, however, by reason of the expansive forces of springs 27 which encircle the pins 28 that depend from 15 the vertex of the frame 10 and have the lower ends thereof deposited in openings 29 which are formed in the top of the marker.

20 In the use of this form of marker it is customary to detachably secure the impactograph in its entirety to the floor of a freight car and to have the clock mechanism start at precisely the time that the rolling stock starts to move. This winds the paper 22 on the take-up drum. If desired, the paper may be 25 suitably graduated so that the time of the occurrence of impacts can be immediately discerned by a glance at the paper roll. If desired, the paper 22 may be sensitized or ordinary paper with interposed carbon 30 sheets may be used, or if desired ordinary paper may be used and the marker 26 either made of a graphic substance or equipped with a graphic means. So long as the rolling stock is not subjected to undue impacts no mark 35 will be made on the paper 22 because of the absence of pressure thereon midway the ends of the segments. However, just as soon as undue impacts are sustained the weights or 40 pendulums 16 will be displaced thereby correspondingly moving the segments 14, causing the paper to be moved upwardly into engagement with the marker 26. If only a slight impact above normal is sustained, the largest of the weights only will be moved to 45 a point whereby the paper will be brought into contact with the marker. The other weights will be selectively displaced, however, as the severity of the impacts increases. When the impacts are very severe the marker 50 26 will be elevated against the resistance of the springs 27 in order to prevent binding or breakage of the parts. It is consequently apparent that this mechanism insures the making of a prompt record of the impact 55 and positively avoids the possibility of the force of an impact of short duration being spent before the recording mechanism is affected.

60 The form of invention shown in Figs. 4 and 5 is similar in principle to that shown in Figs. 1 and 2 but differs therefrom in structural embodiments. In the form of invention shown in Figs. 4 and 5 a frame generally designated 10' is provided, the upper 65 margins of the sides of which are bent out-

wardly at right angles to provide flanges 30, each of which pivotally carries a paper clamping member 31. Mounted through the sides of the frame 10' approximately midway the ends thereof, is a shaft 32 which has pivotally mounted thereon, a plurality of pendulum or weight carrying arms 33, the lower end of each arm issuing into a discal weight 16'. Each of the weights is yieldingly engaged with the base of the frame 10' in the same 70 manner that the weights 16 are engaged with the base of the frame 10 in the form of invention shown in Figs. 1 and 2. Each of the weights 16' has a cylindrical lug 34 extending laterally therefrom at approximately 75 the center of the weight. A channel member 35, of inverted U shape in cross section is mounted above each of the arms 33 on the shaft 32 and is provided with a depending leg 36, the lower end of which is bifurcated 80 and the branches 37 of the bifurcation straddled across the lug 34. Upon reference to Fig. 4 of the drawings it will be noted that each of the members 35 is provided with an angular slot 38 in which the shaft 32 is movably mounted. Furthermore, correspondingly shaped slots 39 are formed in each of the members 35 near the ends of the latter, which receive guide pins 40 carried by the 85 sides of the frame 10'. The upper ends of 90 the arms 33 are spaced in a suitable manner from the sides of the channel members 35 and the latter spaced from one another in an apparent manner. Manifestly, as one of the 95 weights 16' moves on the shaft 32 the channel member is correspondingly moved, the limit 100 of movement being coextensive with the length of the slots 38 and 39.

Upward movement of the channel members 35 causes them to impinge against a record sheet 41 which may be made of sensitized paper or may be made of ordinary paper with carbon sheets interposed therebetween. This paper spans the distance transversely across the sides of the frame 10' and 110 is secured to the tops of the flanges 30 by the clamping members 31.

It is desired that upward movement of the paper 41 will cause impingement of the same against an abutment or scribe in order that 115 a record may be made on the sheet and for this purpose suitable abutment or scribe 42 is movably mounted upon a screw shaft 43. One end of the screw shaft is journaled in one end of the frame 10' while the opposite end is journaled in the opposite end of the frame and extends appreciably therebeyond for insertion in and operative connection with a clock mechanism 44. The stem of the clock mechanism 44 is accessible 125 through one of the openings 9, while one end of the shaft 43 is accessible through the opposite opening 9. Consequently the clock mechanism may be wound, and the scribe or abutment 42 may be moved reversely on 130

the shaft 43 at the option of the user. The scribe or abutment consists generally of a frame 45 which in the present instance is shown to be of oblong configuration and has the lower end thereof formed to provide an elongated abutment member 46, V shape in cross section. A boxing 47 is floatingly mounted in the frame 45 and is provided with a threaded bore which receives the threaded shaft 43. A coil spring 48 is interposed between the boxing 47 and the top of the frame 45 in order to normally force the abutment 46 downwardly toward the record sheet 31. A pin 49 issues from the top of the frame 45 and is positioned to ride in a slot 50 which is formed in the longitudinal axis of a bar 51. The opposite ends of the bar 51 are anchored on the ends of the frame 10'.

Since the abutment or scribe is time operated it is manifest that the time of the occurrence of impacts may be learned from the record sheet 31. The intensity of the impacts is learned by the location of the mark or marks made on the record sheet when any one of the channel members 36 causes the record sheet to be brought into contact with the abutment or scribe. In view of the spring 48 not only will the marker be held in close proximity to the sheet at all times but in addition binding or breakage of the parts will be prevented when impacts of unusual severity are sustained. The weights 16' function in precisely the same manner as the weights 16 in the form of invention shown in Figs. 1 to 3, their movement being selective in correspondence to the intensity of the impact sustained. Furthermore, the weights are immediately displaced as soon as impacts of predetermined intensity are sustained by the rolling stock so that a record is positively made of the impact even though the duration thereof be very short-lived.

It is believed to be manifest, therefore, from the above, that the time of the occurrence of an impact will be promptly recorded and the severity of the impact likewise recorded. I am of course aware that numerous changes may be made in view of the teachings of the present forms of my invention, but I reserve the right to such changes as come within the scope of the claims hereto appended.

What I claim is:

1. An impactograph including mechanism responsive to impacts and embodying selective weight means operable in sequence to harmonize with the intensity of the impacts sustained, and a marker common to all of said means and operable by movement of any one of the latter.

2. An impactograph including displaceable weights of various sizes each of which is equipped with record sheet engaging means, a record sheet arranged in proximity to said means, and an abutment positioned in the

path of movement of said record sheet engaging means whereby movement of any one of the weights urges the sheet into engagement with the abutment for marking the sheet.

3. An impactograph for railway rolling stock including a series of pendulum elements unequal in size for uniplaner displacement by forces of unequal intensity, a record sheet mounted adjacent the pendulums, and an abutment mounted in parallel relation to the record sheet and pendulums whereby movement of any one of the latter will urge the record sheet against the abutment.

4. An impact recorder for railway rolling stock including displaceable means equipped with an indicia receiving medium, said means embodying a plurality of elements selectively displaceable by forces increasing in intensity, and a marker common to all of said elements and operable by movement of any one of the latter to mark said medium.

In testimony whereof I affix my signature.

JOHN B. BASKERVILLE.
